UNITED STATES PATENT OFFICE

PETER WORKMAN, JR., OF KALAMAZOO, MICHIGAN, ASSIGNOR TO SHAKESPEARE COMPANY, OF KALAMAZOO, MICHIGAN

DESIGN FOR A FISHING REEL FRAME

Application filed October 14, 1931. Serial No. 41,384. Term of patent 14 years.

To all whom it may concern:

Be it known that I, PETER WORKMAN, Jr., a citizen of the United States, residing at Kalamazoo, in the county of Kalamazoo and State of Michigan, have invented a new, original, and ornamental Design for Fishing Reel Frames, of which the following is a specification, reference being had to the accompanying drawing, forming part thereof.

Fig. 1 is a side view;

Fig. 2 is a fragmentary front side view in reverse position from that shown in Fig. 1; and

Fig. 3 is an end view of a fishing reel frame, showing my new design.

The dominant feature of my design is the end member of the frame having peripheral A-shaped ribs or beads presenting a plurality of annular angularly related reflecting surfaces.

I claim:

The ornamental design for a fishing reel frame, as shown and described.

PETER WORKMAN, JR.
